UNITED STATES PATENT OFFICE.

HJALMAR LINDESTRÖM, OF CHICAGO, ILLINOIS, ASSIGNOR OF ONE-HALF TO
CHRISTOPHER ANDERSON, OF SAME PLACE.

MOWER.

SPECIFICATION forming part of Letters Patent No. 416,468, dated December 3, 1889.

Application filed August 22, 1889. Serial No. 321,643. (No model.)

To all whom it may concern:

Be it known that I, HJALMAR LINDESTRÖM, a subject of the King of Sweden and Norway, and residing in the city of Chicago, in the county of Cook and State of Illinois, have invented certain new and useful Improvements in Mowers; and I do hereby declare that the following is a full, clear, and exact description thereof, reference being had to the accompanying drawings, and to the letters of reference marked thereon, which form a part of this specification.

This invention relates to improvements in the construction of mowing-machines of that class wherein the reciprocatory movement of the cutter-bar is produced through the medium of a pivoted rocking lever, one end of which is connected to said cutter-bar and the other end of which is attached to a reciprocating bar having at its ends wheels or rollers which engage a scalloped ring-shaped or annular cam upon the main driving-wheel of the machine.

To this end the invention consists in the novel devices and combination of devices herein shown and described, and more particularly pointed out in the appended claims.

The invention relates more particularly to improvements in that class of machines illustrated in Letters Patent No. 404,549, issued to me on the 4th day of June, 1889.

The main feature of novelty in the present application consists in constructing the sliding bar, which carries on each end a wheel or roller to mesh with the scalloped cam on the driving-wheel, in two parts and joining the adjacent ends thereof by a toggle-joint connection, whereby the said wheels or rollers may be thrust into or drawn out of engagement with said cam at the pleasure of the operator.

A second feature of novelty consists in the means employed to permit at all times a vertical adjustment of the cutter-bar, whereby grain of different heights may be cut, combined with the means illustrated for raising the cutter to a vertical position by a lever, the handle of which is in easy reach of the operator.

Another feature of my invention consists in

covering or partially covering the face or faces of the driving-wheel to which the scalloped cam is secured, whereby dirt and other extraneous substances are prevented from clogging or interfering with the work of the scalloped cam, all of which matters will be hereinafter more fully pointed out.

In the drawings, Figure 1 is a side elevation of a machine embodying my invention. Fig. 2 is a plan view of the same partially in section. Fig. 3 is a rear view of the same. Figs. 4 and 5 are vertical sectional views of a portion of the driving-wheel and the cutter-bar operating mechanism, the latter in elevation and in two different positions, the section being taken principally on line 4-4 of Fig. 6, certain parts being shown in elevation that would otherwise appear in section. Fig. 6 is an end view of a portion of the machine partially in section, the section being taken on line 6-6 of Fig. 4. Fig. 7 is a detail perspective view of parts hereinafter set forth.

In the drawings, A is the main frame of the machine, supported by suitable journal-bearings *a* from the shaft or axle A', on each end of which is a driving-wheel A².

A³ is the beam or pole, attached to the frame A in any ordinary manner. The periphery of one of the wheels A² is provided interiorly with a scalloped and toothed cam A⁴, said cam being preferably provided with teeth *a'*. The construction of this wheel is similar to that shown in my said patent, No. 404,549.

A⁵ is a seat for the operator, secured to the frame A.

B B are two sliding bars movably secured upon the frame A, at one end thereof, in suitable guides *b*. Each bar is provided upon its outer and bifurcated end *b'* with a toothed wheel B', which latter is adapted to mesh with the teeth *a'* of the scalloped cam A⁴. The inner or adjacent ends of the bars B are connected together and adjusted in such position with relation to each other and the said cam A⁴ that when in engagement with the cam A⁴ one of the wheels B' will mesh with the teeth in the depression or lowermost portion of the cam, while the other wheel B' will mesh with the teeth on one of the elevated portions of said cam, whereby, by the revolu-

85

90

95

100

tion of the wheel A², the said bars B will receive a reciprocating motion, as will be manifest.

C is a guide-block secured to the frame A on either side of the shaft A', and provided above said shaft with a flat face c, which latter is provided with a T-head slot c'.

C' is a block provided with a suitable T-head c², adapted to fit nicely in the T-head slot c' of the guide C, so as to be moved vertically therein. Projecting from the rear of said block C' is a pin or stud c³, which latter is inserted through an elongated slot or hole c⁴ in the back of the guide C.

15 A convenient way of constructing the foregoing parts is to first insert the head c² of the block C' into the slot c', and afterward insert the pin c³ from the rear through the slot c⁴ and into a suitable opening in the rear face 20 of the head c², within which it can be secured by screw-threads or otherwise.

D is a lever pivoted to the bracket d, which latter is secured to and rises from the frame A. The lever D has an enlarged end d', by 25 which it is secured to the end of the stud or pin c³ of the sliding block C'. It will be obvious that by any movement of said lever D on its pivoted support d the said movement will raise the block C' up or down. The forward end of the block C' is provided with two parallel lugs or flanges c⁵.

C² is a block adapted to fit nicely in the space between the two flanges c⁵, and is provided with an outwardly-projecting pin or 35 stud c⁶.

B² B² are two links constituting a toggle, the lower or outer ends of which links are pivoted at b² to lugs rising from the inner ends of the sliding bars B, while the inner or 40 adjacent ends of said links are pivoted to the said pin or stud c⁶ of the block C².

It will be manifest from the above and by reference to the drawings that the vertical movement of the lever D will raise and lower 45 the block C' and at the same time carry the inner ends of the links B² up or down and thereby withdraw the pinions or wheels B' from engagement with the scalloped cam A⁴, or will cause said wheels B' to engage said 50 teeth, as the case may be, the two positions being illustrated clearly in Figs. 4 and 5 of the drawings.

The construction shown and described permits a slight horizontal motion of the block C², as well as vertical motion of the block C', thus providing for a perfect adjustment of the several parts.

A shaft E is suspended in bearings a³ below and from the frame A, and the ends of the 60 arm E' are pivotally attached to said shaft E. The lower end of this arm E' is pivotally secured by a hinged joint at e to the usual cutter-bar shoe E², whereby said cutter-bar shoe is permitted a slight rotary movement over 65 the end of said arm E', while the arm and shoe at the same time may receive a vertical movement by swinging upon the shaft E. The up-

ward movement of the shoe E² is limited by contact with the rounded end f of an adjustable arm F, suspended from a bearing f' on the beam A³, said rounded end f engaging a socket e² upon the upper side of the end of said shoe E². The upper portion of said arm F is provided with one or more notches f², as shown in Fig. 1.

75 F' is a rod, one end of which is adapted to engage the notches f² on the rod F, while the other end is pivotally attached to a projecting lug f³ upon the pivoted foot-piece F².

f⁴ is a guide secured to the beam A³, and through which the rod F' passes, and f⁵ is a collar secured to the rod F' between said guide and said rod F. f⁶ is a spring interposed between said guide and said collar f⁵, which spring constantly exerts power in the direction of the rod F, and thereby tends to cause the said rod F' to constantly engage the vertical rod F.

It will be manifest from the construction here shown and described that the operator, 90 when sitting upon the seat A⁵, may easily adjust the height to which the shoe E² may be raised by simply putting his foot upon the foot-piece F² and pressing it in such direction as to move the rod F' toward him, whereupon 95 the end of said rod will be disengaged from the bar F, and the latter will fall of its own weight until the rod F is released and its end again engages one of the holes or openings f². The bar F is raised by hand.

100 G is a hand-lever pivoted at its lower end to a shaft or stud g, projecting outwardly from the beam A³, said lever G carrying on its lower end the segment of a drum or pulley g'. Secured rigidly to the beam A³ is another segment 105 g², the periphery of which is provided with a plurality of notches g³, constituting a ratchet adapted to engage the pawl g⁴, which pawl is attached to and is actuated by the handle G' of the lever G in the ordinary manner.

110 G² is a chain or cable secured at its lower end to a plate H, attached to the shoe E². Said chain is secured at its other end to the drum g'. Thus when the pawl g⁴ is disengaged from the teeth or notches g³, and the lever G is 115 moved backward toward the operator, the said chain or cable G² will be wound around the drum g' and thus raise the shoe E² and the cutter-bar carried thereon.

H' is the ordinary cutter-bar, to which the 120 knives H² are secured in the usual manner. Said cutter-bar receives its reciprocating motion from the reciprocating bars B through the following mechanism: Suspended from one of the said bars B is a lug b⁵, to which is 125 bolted or otherwise secured a block b⁶, having upon its inner face a socket b⁷. A bell-crank lever I is pivoted to the frame of the machine at i. One end of said lever is provided with an enlargement or ball i', adapted to fit in 130 the socket b⁷. To the other end i² of this lever I is secured by a hinged joint a lever I', which lever I' passes through a guide e⁴ upon the lower end of the arm E', and is also pro-

vided at its end with an enlargement or ball i^3 . Secured to the cutter-bar H' by a pivotal connection h at one end is a link H^3 , the other end of which link is provided with a socket h' , which engages with and surrounds the ball i^2 upon the end of the lever I' .

It will be understood that the longitudinal movement given to the bars B B by reason of the revolution of the wheel carrying the toothed cam A^4 will produce a reciprocating movement of the ball i' and socket b' , which movement will be communicated to the lever I' , and thus cause a reciprocating movement of the cutter-bar H' .

15 One of the principal advantages of my improvement here shown lies in the fact that all of the parts are simple and straight castings or wrought-iron, and may be quickly and cheaply manufactured, are not easily broken, and are so located with reference to each other and with reference to the work that each separate part performs that the ordinary wear and tear thereon are reduced to the minimum.

25 As a further and separate improvement I have inclosed one face of the driving-wheel A^2 , that carries the toothed cam A^4 , and partially inclosed the other face thereof for the purpose of preventing dirt or grain from getting into the teeth of the scalloped cam-wheel and retarding its work. I accomplish this by means of the web-plates J , secured to the wheel A^2 , between the spokes or ribs thereof. Upon the inner side of said wheel the web J' extends only a short distance toward the center, and is, in fact, an annular rim having upon its inner edge an inwardly-turned rim or flange j , for the purpose of deflecting the dirt and earth away from the working parts of the 40 wheel.

When the cutter-bar H' is raised in the vertical position for the purpose of transporting the machine from one field to another, I disengage the wheels B' from contact with the scalloped cam A^4 by depressing the lever D , as shown in Fig. 5. Thus the wheels A^2 may be revolved at pleasure without causing a reciprocating movement of the knife-blades H^2 when the cutter-bar is in a vertical position.

50 D' is a spring secured to the frame, having its free end in engagement with the short arm d^2 of a second lever D^2 , pivoted to the lever D . The spring D' tends to keep said arm d^2 in frictional contact with the frame A , as clearly shown in Figs. 4 and 5. To raise the lever D , I first press on the handle of the lever D^2 and thus draw the short arm d' upwardly. I sometimes find it convenient to 60 provide one or more holes d^3 in the frame A and place a small pin or stud d^4 in the short arm d^2 , adapted for engagement with said hole d^3 when said lever is depressed. In such case a strong pressure on the handle of the lever D^2 toward the lever D will cause 65 said pin to be disengaged from said hole, as will be obvious.

When it is desired to raise the cutter-bar to an upright position, the operator drops the arm F , so that its rounded end f will engage 70 the socket e^2 of the shoe E^2 . The operator then draws up the chain G^2 by depressing the handle of the lever G , whereupon the cutter-bar is raised, the socket e' and rounded end f becoming a fulcrum.

75 What I claim is—

1. The combination, with the frame and cutter-bar of a mower, of a driving-wheel provided with an annular scalloped toothed cam, a reciprocating two-part bar on said frame, provided with two wheels or pinions adapted to intermesh with said toothed cam, a toggle uniting the inner ends of said bars, a block C^2 , uniting the inner ends of said toggle, a vertical sliding block C' , having a 85 horizontal guide within which the block C^2 slides, and a lever connected with said block C' for elevating and depressing the same, whereby the two parts of the reciprocating bar may be moved toward and from each 90 other, substantially as described.

2. The combination, with the frame and cutter-bar of a mower, of a driving-wheel provided with an annular scalloped toothed cam, a reciprocating two-part bar on said 95 frame, provided with two wheels or pinions adapted to intermesh with said toothed cam, a toggle uniting the inner ends of said bar, a block C^2 , uniting the inner ends of said toggle, a vertically-sliding block C' , provided 100 on its front face with two horizontal and parallel lugs or flanges c^5 c^6 , between which the block C^2 fits and slides, and a lever connected with said block C' for elevating and depressing the same, substantially as described.

105 3. The combination, with a frame and cutter-bar of a mower, of a driving-wheel provided with an annular scalloped toothed cam, a reciprocating two-part bar on said frame, provided with two wheels or pinions adapted 110 to intermesh with said toothed cam, a toggle uniting the inner ends of said bar, a block C^2 , uniting the inner ends of said toggle, a block C' , provided on its front face with a horizontal guide within which the block C^2 fits and 115 slides, said block C' being provided with a T -head, a vertical guide C , provided with a T -head slot c' , within which the said T -head of the block C' fits and slides, and a lever connected with said block C' for elevating and 120 depressing the same, substantially as described.

4. The combination, with the frame and cutter-bar of a mower, of a driving-wheel provided with an annular scalloped toothed 125 cam, a reciprocating two-part bar on said frame, provided with two wheels or pinions adapted to intermesh with said toothed cam, a toggle uniting the inner ends of said bar, a block C^2 , uniting the inner ends of said toggle, a block C' , provided with a horizontal 130 guide within which the said block C^2 fits and slides, said block C^2 being provided with a T -head c^2 and a pin c^3 in said head c^2 , a verti-

cal guide C, provided with a T-head slot c, a slot or hole c¹ in the rear portion of said guide C, and through which the pin c³ projects, and a lever connected with said pin for elevating 5 and depressing the said block C', substantially as described.

5. The combination, with the frame and cutter-bar of a mowing-machine, of a drive-wheel provided with an annular scalloped 10 toothed cam, a reciprocating bar provided with toothed wheels or pinions adapted to intermesh with said toothed cam, a bent lever pivoted to the frame of the machine, the short arm of which is pivotally secured to 15 said reciprocating bar and the long arm of which is pivotally secured to the cutter-bar, said long arm being provided with a hinged or pivoted joint, whereby the said cutter-bar may be elevated or depressed independently 20 of the movement of said short arm, substantially as specified.

6. The combination, with the frame of a

mowing-machine and a shoe having a cutter-bar attached thereto, of an adjustable bar, as F, secured to the frame or beam of the machine independently of the cutter-bar and having its lower end adapted to engage the said shoe when the latter is raised, of a drum secured to the frame or beam, a lever provided with a pawl and ratchet secured to said 25 drum and adapted to operate the same, and a chain or cable one end of which is secured to the drum and the other end of which is secured to the cutter-bar, whereby by a movement of said lever the cutter-bar may be 30 raised to an upright position, substantially as specified.

In testimony that I claim the foregoing as my invention I affix my signature in presence of two witnesses.

HJALMAR LINDESTRÖM.
